Primary Examiner — Brett Miller*Assistant Examiner* — Nader Abadir(74) *Attorney, Agent, or Firm* — Mintz, Levin, Cohn, Ferris, Glovsky and Popeo, P.C.(57) **CLAIM**

The ornamental design for an outdoor grill, as shown and described.

DESCRIPTION

FIG. 1 is a front perspective view of an outdoor grill; FIG. 2 is a front view of the outdoor grill of FIG. 1; FIG. 3 is a rear view of the outdoor grill of FIG. 1; FIG. 4 is a left view of the outdoor grill of FIG. 1; FIG. 5 is a right view of the outdoor grill of FIG. 1; FIG. 6 is a top view of the outdoor grill of FIG. 1; and, FIG. 7 is a bottom view of the outdoor grill of FIG. 1. The broken lines shown in the drawings depict portions of the outdoor grill that form no part of the claimed design.
